UNITED STATES PATENT OFFICE.

FREDERICK C. WARNE, OF MANSFIELD, OHIO.

DISK HARROW.

Application filed December 10, 1917. Serial No. 206,533.

To all whom it may concern:

Be it known that I, FREDERICK C. WARNE, a citizen of the United States, residing at Mansfield, in the county of Richland and 5 State of Ohio, have invented certain new and useful Improvements in Disk Harrows, of which the following is a specification.

My invention relates to improvements in disk harrows, and more particularly to that 10 class or type known as "double" or "tandem" disk harrows in which front and rear units are employed, each unit embodying a pair of adjustably mounted rotary disk gangs adapted to be angled or turned in opposite directions relative to each other and 15 to the line of draft as disclosed for example in my Patent No. 1,189,890, of July 4th, 1916.

This invention further relates to that class 20 or type of double disk harrows known as "engine disk harrows," the present improvements being particularly designed and adapted for use in connection with an engine or tractor, and with this end in view, 25 my improvements relate particularly to improve draft connections for such implements and means whereby the disk gangs thereof may be readily moved to and secured in any desired angular position relative to each other and to the line of draft by the operator of the tractor while in the 30 seat or cab of the latter, the construction and arrangement of the parts being such that when the disk gangs are locked in their 35 normal working or fully angled position, or in an intermediate angled position, and are relatively released or unlocked by the operator while the tractor is in motion, such disk gangs will automatically assume 40 through such draft connections their non-working or non-angled transporting position, or less angular working position, as the case may be, and as the operator may elect, and may be stopped and locked in 45 such elected position while the tractor is in motion. Furthermore, if desired, the disk gangs may be manually moved to a more angular or to a fully angled working position 50 while in motion with a minimum expenditure of energy by the operator, and they may also be readily and quickly moved manually in a straightening direction by the operator as desired when the implement is at rest.

A further object is to provide a generally 55 improved leverless disk harrow of this class having its parts so constructed, arranged and disposed relative to each other as to give the requisite strength, flexibility and general adjustability which experience and 60 the varying demands of actual service have shown to be necessary or desirable, and to this end I provide two draft or reach bars pivotally connected to the rear unit or section and extending forwardly and in converging relation to each other and pivotally connected to the front unit or harrow section at two points equally distant from the longitudinal center of the harrow or line of draft as disclosed in my said patent 70 hereinbefore referred to.

With the above mentioned and other ends in view, the invention consists in the novel construction, arrangement, and combination of parts, hereafter described, illustrated in 75 one of its embodiments in the accompanying drawings, and particularly pointed out in the appended claims.

Referring to the drawings, forming a 80 part of this specification, Figure 1 is a top plan view of a disk harrow constructed in accordance with this invention, the disk gangs being in their non-working or non-angled transporting position, the gang angling or controlling hand wheel being removed, and certain portions of the draft connections being broken away and shown in section for the purpose of clearer illustration of the parts.

Fig. 2, a similar view, the disk gangs being in their extreme angled or working positions, the central or relatively movable draft block and its connected draft and reach bars attached to the inner ends of the front disk gangs and to the pivoted portions 95 of the rear disk gangs, respectively, being in their relatively rearmost positions.

Fig. 3, a detailed perspective view of the movable draft block and its connections disassembled.

Fig. 4, a perspective view of the front draft frame and its relatively movable draft block and connections, together with the controlling and operating mechanism therefor, the disk gangs being shown in their non-angled or transporting position.

Fig. 5, a central longitudinal sectional view of the same

Fig. 6, a similar view, the draft bar being shifted to its rearmost position to permit its draft connections to shift in a like direction and permit the disk gangs connected therewith to assume their angular positions.

Fig. 7, an enlarged detailed view of the draft rack and block controlling shaft and hand wheel, together with the locking or detent mechanism therefor, the latter being 10 in unlocked position.

Fig. 8, a detailed perspective view of the lower end of the controlling shaft and its bearings and operating pinion in disassembled position.

15 Fig. 9, a perspective view of the draft rack and bar, detached.

Fig. 10, a perspective view of the hand wheel locking bar or detent, detached.

Similar numerals of reference designate 20 like parts throughout all the figures of the drawings.

The improved harrow or tillage implement comprises a front harrow section or unit and a rear or trailing harrow section 25 or unit. The front and rear harrow sections or units may be of any suitable or conventional form and for the purposes of illustration I have shown my improved draft appliance and its connections applied to or embodied in a double or tandem disk harrow of the general form of that disclosed in my former patent hereinbefore referred to.

The front harrow section or unit is provided with a suitable draft frame consisting, 35 in the present instance, of a transverse bar 1, and a curved draft frame member 2, the latter having its forward middle portion secured to a sub-pole 3, which latter is made up of spaced angle bars secured at their 40 rear to the transverse bar or member 1, and, in the present instance, forming a guide or slideway for the improved longitudinally movable draft appliance hereinafter described.

45 As a means of connecting the draft frame to the front disk gangs 4, draft bars or links 5, are pivotally connected to filler blocks 2^a, said draft bars extending rearwardly beneath the transverse bar 1, and being flexibly connected to axle boxes 6, somewhat beyond the centers of the disk gangs so that the inner ends of the latter will normally have a tendency to swing rearwardly and assume a rearwardly converging position.

55 As a means of supporting and maintaining the draft bars 5, in proper horizontal relation to the transverse bar 1, supporting clips 7, are pivotally mounted upon the filler blocks 2^a, and are secured by means of the 60 pivot bolts 5^a, securing the forward ends of the draft bars 5, said clips 7, extending rearwardly and being secured to the top intermediate portions of the bars 5, by means of pivot bolts 7^a, and as a further means of 65 securing the draft frame to the front disk

gangs draft bars or links 8, are connected by the pivot bolts 5^a, above the supporting clips 7, and extend upwardly and rearwardly and are flexibly connected to the upper or transverse bars 9, of the front gang frames by 70 means of pivot bolts 9^a. The gang frame bars 9, are connected to the disk gangs 4, by means of supporting bracket or brace members 9^b, extending downwardly and suitably secured to axle boxes 9^c. 75

The bars 9, of the gang frames are provided, in the present instance, with scrapers 10, extending along the concaved sides of the disks of the disk gangs and held in proper spaced relation to each other by means of bars 10^a.

The rear harrow section or unit, in the present instance, comprises a pair of rear disk gangs 11, suitably mounted and supported in gang frames 12, the latter being 85 provided with supporting brackets 12^a, connected to axle boxes 12^b.

The rear disk gangs 11, in the present instance, are pivotally connected and held in proper spaced relation at all times by means of a transversely extending rear harrow frame 13, provided at its ends with bearing blocks 13^a, carrying pivot bolts 14, suitably connected to the gang frames 12, of the rear gangs. In the present instance, the gang frames 12, are also provided with scrapers 15, similar to the scrapers 10, of the front gang frames. It will also be observed that the pivot or swivel bolts 14, are located beyond the centers of the rear gang frames so that the inner ends of the rear gangs will have a tendency to swing rearwardly and assume a rearwardly converging angle when permitted to swing on their pivots 14.

As a means of connecting the inner ends of the rear gangs 11, to the front harrow sections, longitudinally extending draft bars 16, are provided, said bars being connected at their rear ends to eye members 16^a, of the gang frames, and being also provided with brace members 16^b, suitably secured to the bearing axle blocks at the inner ends of the rear gangs, the forward ends of the bars extending downwardly and, in the present instance, being connected to the transverse bar 1, of the front draft frame by means of bearing plates 17, adjustably secured to the bar 1, by means of securing bolts 17^a, the depending rounded or bearing portions 16^c, of the draft bars 16, being adapted to have a limited movement in the bearing plates 17, as in turning corners, and the like, by being mounted in slots 17^b, of the plates 17. 115 As compared with the movements of the draft bars attached to my improved draft appliance hereinafter described, these draft bars 16, together with the draft bars or links 5 and 8, may be described as being "longitudinally fixed" relative to the frame members and in order that the functions of the 120 125 130

draft appliance and its longitudinally movable draft bars may be performed as hereinafter described.

I shall now refer to the improved draft appliance and its gang connecting, adjusting and controlling mechanism. This improved draft appliance comprises a longitudinally movable draft member or element, mounted, in the present instance, in the stub-pole 3, of the draft frame, and consisting, in the present instance, of a draft block or head 18, adapted to slide between the angular members of the stub-pole 3, said block 18, being controlled by a longitudinally movable draft bar 19, connected, in the present instance, to a draft yoke or clevis 20.

The bar 19 is provided with a slot 19^a (Figs. 5 and 9) adapted to receive the pin 18^a secured to the sliding block 18. The draft clevis 20 is provided with a rack 20^a with which meshes the pinion 24 upon the lower end of the vertical shaft 21 (Figs. 5 and 8). The lower end of this shaft is mounted in bearing blocks 23 secured to the stub pole 3 by means of bolts 23^a (Fig. 8), and the upper end in the bearing head 26 supported by bracket arms 25 extending from the frame.

To the upper end of the shaft 21 is secured the hand wheel 22, and the ratchet 22^a, with which the pawl 27, beveled at 27^b, cooperates. This pawl is mounted in the opening 26^a of bearing head 26 and is normally pressed upward by spring 27^a into contact with the ratchet teeth to prevent the rotation of the ratchet, shaft, hand wheel, pinion 24, etc., in a contra-clockwise direction as viewed in Fig. 4. In other words, the pawl and ratchet mechanism normally prevents the forward movement of the rack 20^a and the draft clevis 20 of which it forms a part. The pawl 27 may, however, be withdrawn from the ratchet 22^a, and the draft clevis thus released for forward movement, by manually swinging the pivoted cam-headed lever 28 into a horizontal position as shown in Fig. 7. The hand wheel 22 and the releasing lever 28 are so positioned that they may be manipulated by the person who is operating the tractor without moving from his seat.

As above stated, the outer portions of the front gangs are connected to the draft frame by the draft bars or links 5, and the inner ends of the rear gangs are similarly connected to that frame by the draft bars or links 16. The inner ends of the front gangs and the outer portions of the rear gangs are not connected directly to the draft frame but to the sliding head 18 which is mounted on the stub pole as above described. The connections from the sliding block 18 to the inner ends of the front gangs comprise the longitudinally movable draft bars 29, which are connected to the gangs through the me-

dium of the pivot bolts 29^a, secured to the inner axle boxes 9^c. The draft connections leading from the draft block or head 18, to the rear gangs and draft frame comprise rearwardly diverging draft or reach bars 30, the latter, in the present instance, being pivotally connected to the pivoted portion of the rear gangs by means of bearing plates 31, and bearing bolts 31^a, said bearing plates 31, being suitably secured to the gang frames 12, and surrounding the pivot bolts 14, and by reason of this construction it will thus be seen that the draft or reach bars 30, are indirectly connected to the outer ends of the rear harrow frame 13, and it will also be observed that the rear ends of the draft or reach bars 30, are provided with downwardly and rearwardly extending brace members 29^b, suitably secured to the central axle bearing boxes of the rear disk gangs. 75

The forward ends of the draft bars 29, and 30, may be pivotally or flexibly secured to the draft block or head 18, in any suitable and convenient manner, such connecting means, in the present instance, comprising swivel eye bolts 32, passing through suitable openings in bearing plates 18^b, secured to the upper and lower sides of the draft block or head 18, by means of securing bolts 18^c, and bearing, in the present instance, on the upper and lower sides of the stub-pole 3, and as a means of conveniently connecting the forward or depending ends of the draft bars 30, to the eye bolts 32, cross bearing bolts 33, may be provided to extend through the eyes of the bolts as shown. As a convenient means of pivotally connecting the forward ends of the draft bars 29, to the block or head 18, the latter may be provided on its under side with a bearing plate 100 or bracket 18^d (see Fig. 3), said plate 18^d, being provided at its sides with upturned bearing ears or lugs 18^e, extending on the outer sides of the stub-pole and provided with bearing bolts 18^f, through the medium 105 of which the forward ends of the draft bars 29, may be readily attached.

Upon reference to the construction herein shown and described it will be seen that the draft bars 5 and 16, extending from the draft frame connect to the pivoted and inner ends of the front and rear disk gangs, respectively, and are substantially longitudinally fixed relative to the front and rear harrow frames, while the draft bars 29 and 30, leading from the draft block or head 18, and connected to the inner and pivoted portions of the front and rear disk gangs, respectively, are longitudinally movable relative to said draft frame and said draft links 5 and 16, connected therewith. 115

By reason of the construction above described it is possible for the operator to adjust the angles of the gangs, and to angle and straighten them automatically through 120 125 130

the movement of the tractor or other draft power employed, and without leaving his station. Thus, if the gangs are straight or at an angle less than that desired, the operator may back the tractor or other power source and thus back the draft clevis 20 an amount corresponding to the desired angle. He may then advance the tractor or other power source and by so doing throw the gangs into the angle set. So, also, if while the gangs are angled the tractor or other power source is backed to such an extent as to back the entire harrow, the gangs will straighten, but will normally be again angled on the next forward pull. To straighten the gangs on a forward pull, it is necessary merely to release the pawl 27 by manipulation of the handle 28 which is readily accessible from the driver's seat.

I shall now describe the operation of my harrow more in detail. First assume that the gangs are in their straight or non-working position as illustrated in Figs. 1, 4 and 5. The clevis 20 is then in its foremost position and the pin 18^a of head 18 is at the rear of the slot 19^a of the clevis. To set the angle into which the gangs are to be thrown the clevis 20 is now backed, either by the draft power or manually through the hand wheel 22 or otherwise. For a full angle it is moved completely back into the position shown in Fig. 6 where the pin 18^a is at the front end of slot 19^a. The pawl and ratchet mechanism 22^a, 27, allows this rearward movement of the clevis. But if now pulling force is applied to the clevis, the clevis is prevented by the pawl and ratchet from moving forward relative to the stub pole. As a result the entire harrow is advanced. In the advance of the harrow the resistance of the ground retards the portions of the gangs which are connected to the slideable head 18 and which are therefore free to move rearwardly relative to the draft frame (i. e., the inner ends of the front gangs and the outer portions of the rear gangs). This retardation, accompanied by the relative rearward movement of the sliding head 18 continues until the pin 18^a of the head abuts against the rear end of the slot 19^a of the clevis, or, in other words, until the gangs have attained the angle for which the clevis was set. Fig. 2 illustrates the position of the parts after the gangs have been thrown into full angle in the manner above described.

If, with the parts in the position shown in Fig. 2, the harrow is backed, the inner ends of the front gangs and the outer portions of the rear gangs, being connected to the sliding head 18 which is now free to move forwardly relative to the draft frame, will be retarded by the resistance of the ground and will therefore move relatively forward until the pin 18^a abuts against the forward end of the slot 19^a. When this occurs the parts

will be in the position of Fig. 6, and the gangs will be straight. What I have just described is the straightening of the gangs in backing, and is just the opposite operation from angling the gangs by a forward pull.

Another way of straightening the gangs is by releasing the pawl 27 and applying a forward pull to the draft clevis. Thus, if the pawl 27 is released by the hand lever 28 with the parts in the angle position shown in Fig. 2, a forward pull applied to the draft clevis will pull forward the block 18 on the stub pole and with it the inner ends of the front gangs and the outer portions of the rear gangs. In this way the gangs may be returned to the straight position of Fig. 1, or their angle may merely be reduced, depending upon how long the pawl is held out of engagement with the ratchet.

From the foregoing description, taken in connection with the accompanying drawings, the operation and advantages of my invention will be readily understood.

Having thus described one of the embodiments of my invention, what I claim and desire to secure by Letters Patent, is,

1. In a tillage implement, a plurality of tillage gangs arranged in front and rear pairs, and relatively longitudinally fixed and movable draft connections flexibly connected to the inner and intermediate portions of said front and rear pairs of gangs and means for actuating the movable connections by the forward draft on the implement for angularly adjusting the gangs.

2. In a tractor drawn tillage implement, tandem frame units and angularly adjustable tillage gangs carried thereby, and relatively adjustable draft means flexibly connected to said frame units and gangs and movable by the forward draft of the tractor for adjusting the relative positions of said frame units and gangs while in motion.

3. In a tractor drawn tandem tillage implement, flexibly connected tandem frames, comprising draft connections between said frames movable relatively to each other and operable by the forward draft of the tractor for relatively adjusting said frames.

4. In a tractor drawn tillage implement, tandem frames and tillage gangs carried thereby, and relatively shiftable draft connections flexibly connected to said frames and gangs and forwardly and rearwardly movable relative to each other by the draft of the tractor for angularly adjusting said gangs while in motion.

5. In a tractor drawn tandem tillage implement, front and rear frame units including horizontally movable pivoted tillage gangs, and relatively movable draft means connected to said frame units and gangs and operable in one direction by the implement drawing tractive force for angularly adjusting the gangs.

- adjusting said frame units and gangs relative to each other.
6. In a tandem tillage implement, tandem frame units and pivoted tillage gangs carried thereby, and draft connections forwardly and rearwardly movable relative to said units and flexibly connected to the inner and outer portions of said tillage gangs and operable by the forward draft on the implement for moving and adjusting said frame units and gangs.
7. In a tillage implement, tandem frame units and tillage gangs, draft connections flexibly connected to said units and gangs, some of said draft connections being forwardly and rearwardly movable relative to one of said tandem frame units, and means for adjusting said last mentioned draft connections relative to the others for moving said gangs in varying angular relation.
8. In a tillage implement, front and rear frame units carrying pivoted tillage gangs, and relatively movable draft connections flexibly connected to said frame units and tillage gangs, some of said draft connections being substantially longitudinally fixed to one of the frame units and secured to the free ends of the gangs of the opposite frame unit and the others being forwardly and rearwardly movable relative to said front unit by the forward draft of the implement for angularly adjusting said gangs through the relative draft movements of said frame units.
9. In a tractor drawn double disk harrow, front and rear units, front and rear pivoted disk gangs on said units, and a relatively movable draft appliance provided with draft bars connected to the inner and intermediate portions of said front and rear disk gangs, respectively.
10. In a disk harrow, front and rear harrow frames, disk gangs pivotally connected therewith, a draft head movable relative to said front harrow frame, means for adjusting and locking said draft head relative to said front frame, and draft bars pivotally connected to said draft head and to the inner and intermediate portions of said front and rear disk gangs, respectively.
11. In a disk harrow, the combination with front and rear harrow sections each provided with adjustably connected disk gangs; of an adjustable draft appliance on said front harrow section including draft bars connected to the inner and intermediate portions of said front and rear disk gangs, respectively.
12. In a tractor drawn double disk harrow, front and rear units including front and rear pivoted disk gangs, substantially longitudinally fixed draft bars on said front unit flexibly connected to the pivoted and inner portions of said front and rear disk gangs, respectively, and a relatively movable draft appliance provided with draft connections connected to the inner and intermediate portions of said front and rear disk gangs, respectively.
13. In a disk harrow, the combination with front and rear harrow sections each provided with adjustably connected disk gangs; of a relatively movable draft member provided with draft bars connected to the inner ends of said front disk gangs, and means for moving said draft member and harrow sections relative to each other, including reach bars flexibly connected to said rear harrow section and draft member.
14. In a disk harrow, front and rear harrow frames, disk gangs pivotally connected therewith, a draft member slidably carried by said front harrow frame, and means for connecting, adjusting, and locking said draft member and front harrow frame in various relative positions to each other, said means including draft bars pivotally connected to said draft member and to the inner and pivoted portions of said front and rear disk gangs, respectively.
15. In a tandem disk harrow, front and rear harrow frames and pivoted disk gangs, substantially longitudinally fixed draft bars connected to said front harrow frame and certain intermediate and inner portions of said disk gangs, a relatively movable draft appliance connected to the opposite inner and intermediate portions of said front and rear disk gangs, and means for adjusting and locking said draft appliance in various gang angling relations to the line of draft.
16. In a tractor drawn tandem disk harrow, front and rear harrow frames, a plurality of pivoted front and rear disk gangs, and a relatively movable draft appliance adjustably connected to said front harrow frame and bars connected to the inner and pivoted portions of said front and rear disk gangs, respectively, whereby the latter when angled will automatically assume less angular relations to each other when said draft appliance is released and moved forwardly by the tractive force relative to said front harrow frame.
17. In a tractor drawn tandem disk harrow, front and rear frames each provided with a plurality of angularly adjustable disk gangs, a relatively movable draft appliance connected to the inner and pivoted portions of said front and rear disk gangs, respectively, and normally fixed to the front frame and means for releasing said draft appliance whereby said disk gangs will automatically assume variable angular working positions while in motion.
18. In a tractor drawn tandem disk harrow, front and rear harrow frames each provided with a pair of pivoted disk gangs, and a relatively movable adjustable draft appliance provided with parallel and rear-

- wardly diverging draft bars connected to the inner and pivoted portions of said front and rear disk gangs, respectively, and normally fixed to the front frame whereby the latter when angled and released will automatically assume through movement of said draft appliance by the tractive force less angular and parallel relations to each other.
19. In a tandem disk harrow, front and rear harrow frames and disk gangs, substantially longitudinally fixed draft bars connected to said front harrow frame and certain intermediate and inner portions of said disk gangs, a longitudinally movable draft appliance flexibly connected to the opposite inner and intermediate portions of said disk gangs, and means for adjusting and locking said draft appliance in various gang angling relations to the line of draft.
20. A disk harrow, comprising front and rear harrow sections, adjustably mounted front and rear disk gangs, draft bars flexibly connected to said front harrow section and the intermediate and inner portions of said front and rear disk gangs, respectively, a draft appliance provided with draft bars flexibly connected to the inner ends of said front disk gangs and to rear harrow section, and means for moving and adjusting said draft appliance relative to said front harrow section whereby to simultaneously move and adjust said disk gangs in various relative angular positions to the line of draft.
21. An engine drawn tandem disk harrow, comprising front and rear harrow sections each provided with pivotally mounted disk gangs, longitudinally fixed draft bars flexibly connected to said front harrow section and the intermediate and inner portions of said front and rear disk gangs, respectively, and a longitudinally movable draft appliance carrying longitudinally movable draft bars flexibly connected to the inner ends of said front disk gangs and the pivoted portions of said rear disk gangs, and means for locking and releasing said draft appliance relative to one of said harrow sections whereby when released to simultaneously and automatically move and adjust said disk gangs in various converging angular positions to each other through the engine draft on said draft appliance while in motion.
22. In a tractor drawn double disk harrow, front and rear harrow frames, front and rear pivoted disk gangs, laterally movable draft links flexibly connected to said front harrow frame and the pivoted and inner portions of said front and rear disk gangs, respectively, a tractor draft appliance provided with longitudinally movable draft bars flexibly connected to the inner and pivoted portions of said front and rear disk gangs, respectively, and means operable from a tractor for moving and locking
- said draft appliance and longitudinally movable draft bars independently of and relatively to said front harrow frame and draft links whereby said disk gangs may be simultaneously angled in various adjusted positions through said longitudinally movable draft appliance while the latter is in motion.
23. In a tractor drawn tillage implement, flexibly connected tandem tillage gangs and draft connections between said gangs movable relatively to each other through the relative draft movements of the tractor for relatively adjusting said gangs.
24. In a tractor drawn tillage implement, tandem tillage gangs, and relatively adjustable draft means flexibly connected to said gangs and movable by the relative draft movements of the tractor for adjusting the relative positions of said tillage gangs.
25. In a tractor drawn tillage implement, tandem tillage gangs, a draft appliance and relatively fixed and movable draft means flexibly connected to said gangs and movable by the relative movements of the tractor for changing the relative positions of said tillage gangs.
26. In a tractor drawn tillage implement, flexibly connected tandem tillage gangs, a movable draft member and relatively fixed and movable draft connections to said gangs movable relatively to each other through the movements of said draft member by the tractor for relatively adjusting said gangs.
27. In a tractor drawn tillage implement, a plurality of tillage gangs, relatively longitudinally fixed and movable draft connections flexibly connected thereto, and means for actuating the movable connections by the forward draft on the implement whereby said gangs are moved relatively of each other.
28. In a tractor drawn tillage implement, including a plurality of tillage gangs, relatively longitudinally fixed and movable draft connections flexibly attached to the inner and intermediate portions of said gangs, and means for adjusting the movable draft connections by the forward draft on the implement for moving said gangs in variable relative positions to each other.
29. In a tractor drawn tillage implement, including a plurality of tandem tillage gangs, relatively fixed and movable draft connections flexibly attached to said gangs, and means for adjusting the movable draft connections through the movements of the tractor relative to the implement for moving said gangs in variable relative angular positions to each other.
30. In a tractor drawn tillage implement, tandem tillage gangs, and relatively fixed and movable draft members flexibly connected to said gangs, said movable draft members being actuated in one direction by

- the implement drawing tractive force for moving said tandem gangs relatively to a less angular position and in an opposite direction to a more angular position.
- 5 31. In a tractor drawn tillage implement, tandem tillage gangs, draft connections flexibly connected to said gangs, some of said draft connections being forwardly and rearwardly movable relative to the other and 10 adapted to move said gangs in opposite angular relation to each other through the relative movements of the tractor, and means for locking said draft connections and gangs in variable relative positions to 15 each other.
32. In a tractor drawn tillage implement, tandem tillage gangs, draft connections flexibly connected to said gangs, some of said draft connections being forwardly and rearwardly movable relative to the other at 20 points of connection on said gangs opposite the latter and adapted to move said gangs in opposite angular relation to each other through the relative movements of the tractor, and means for locking said draft connections and gangs in variable relative positions to 25 each other.
33. In a harrow, front and rear frames, disk gangs carried thereby, means for automatically straightening said rear gangs in 30 backing and means for setting an angle for the rear gangs in backing and for assuming the angle so set on the next forward pull.
34. In a harrow, front and rear harrow units, disk gangs on said units, means connecting said units, means operable by the draft power for setting the angle in both sets of gangs by backing, and means for putting the gangs into angle by a pull.
35. In a harrow, front and rear frames, disk gangs carried thereby, means for automatically straightening said gangs in backing and means for setting an angle for the 45 gangs in backing and for assuming the angle so set on the next forward pull.
36. In a harrow, front and rear frames, disk gangs carried thereby, means for straightening said rear gangs in backing and means for setting an angle for the rear gangs in backing and for assuming the angle so set on the next forward pull.
37. In a harrow, front and rear frames, disk gangs carried thereby, means for automatically straightening said rear gangs in 55 backing, and means including a draft device for setting an angle for the rear gangs in backing and for assuming the angle so set on the next forward pull.
38. In a harrow, a frame, disk gangs carried thereby, a draft device adapted to receive the pull of the harrow, said device being slidale with respect to said frame, ratchet means for locking said draft de-
- vice with respect to said frame and releasing 65 means operable from a point outside the harrow.
39. In a harrow, front and rear sections, disk gangs carried thereby, draft means, means for setting the angle of both gangs by a push on said draft means while the gangs are still substantially straight, and means for causing the gangs to assume the angle so set on a forward pull on said draft means. 70
40. In a harrow, front and rear sections, disk gangs carried thereby, draft means, means for setting the angle of both gangs by a push on said draft means while the gangs are still substantially straight, means 75 for causing the gangs to assume the angle so set on a forward pull on said draft means, and means for releasing the angle on a forward pull.
41. In a harrow, front and rear sections, disk gangs carried thereby, draft means, means for setting the angle of both gangs by a push on said draft means while the gangs are still substantially straight, means 80 for causing the gangs to assume the angle so set on a forward pull on said draft means, and means operable from a point outside the harrow for releasing the angle on a forward pull.
42. In a harrow, front and rear frames, disk gangs carried thereby, means operable by the draft power for automatically angling the rear gangs, and means controllable from a point outside the harrow for causing the draft power to straighten said rear gangs by a forward pull. 85
43. In a harrow, front and rear frames, disk gangs carried thereby, means operable by the draft power for automatically angling said gangs, and means controllable from a point outside the harrow for causing the draft power to straighten said gangs by a forward pull. 90
44. In a harrow, front and rear units, disk gangs on said units, means connecting said units, and means controllable from a distance for causing the forward pull of the draft power either to straighten or to angle said gangs. 100
45. In a harrow, angularly adjustable disk gangs, means to which power is adapted to be applied for advancing said harrow, and means operatively related to said first mentioned means and to said gangs and controllable from a distance, whereby the draft power may be utilized to adjust the angles of said gangs. 115
46. In a harrow, front and rear units, angularly adjustable disk gangs on said units, means to which power is adapted to be applied for advancing said harrow, and means operatively related to said first mentioned means and to said gangs and con- 120

- trollable from a distance, whereby the draft power may be utilized to adjust the angles of said gangs.
47. In a harrow, a draft frame, angularly adjustable disk gangs, means movably mounted upon said frame and flexibly connected to said gangs, a draft device also movably mounted upon said frame, and means providing a lost motion connection between said first mentioned means and said draft device.
48. In a harrow, a draft frame, angularly adjustable disk gangs, means movably mounted upon said frame and flexibly connected to said gangs, a draft device also movably mounted upon said frame, means providing a lost motion connection between said first mentioned means and said draft device, and means controllable from a point outside the harrow for locking said draft device to said frame.
49. The combination with a tractor having a draft device, of an earth engaging element; and a setting and tripping draft connection between the tractor and said element, whereby when the tractor is advanced said connection interlocks at selective positions to determine the effective ground engaging angle of said element.
50. The combination with a tractor having a draft device, of an earth engaging element; and a setting and tripping draft connection between the tractor and said element, whereby when the tractor is advanced said connection interlocks at selective positions to determine the effective ground engaging angle of the earth engaging element, and by which means the earth engaging element can be moved to inoperative position while the tractor is still advancing and is attached to the tractor.
51. The combination with a tractor having a draft device, of an earth engaging element; and a setting and tripping draft connection between the tractor and said element, said connection locking the earth engaging element in operative position when the tractor is advanced and operative to adjustably interlock at a selected one of a plurality of positions when the tractor is backed up after said element has been moved to inoperative position.
52. In a harrow, tandem frame units and tillage gangs, a relatively fixed draft guide on one of said frame units, relatively movable draft connections guided by said guide and connected to the inner and intermediate portions of said front and rear tillage gangs, respectively, and relatively longitudinally fixed draft connections connected to one of said frame units and the opposite inner portions of said rear tillage gangs. 55
53. In a tillage implement, front and rear harrow frames, front and rear tillage gangs, a fixed central draft guide on said front harrow frame, a movable draft appliance on said guide, a guide head on said movable draft appliance connected to the inner ends of said front tillage gangs, draft links extending from the latter to said draft appliance, draft means connecting said draft appliance to the intermediate portions of said rear tillage gangs, and longitudinally fixed draft links connected to said front harrow frame and the inner ends of said rear tillage gangs. 60
54. In a tractor drawn tillage implement, front and rear harrow frames, pairs of tillage gangs pivotally connected thereto, a central relatively fixed draft member forming a guide on said front harrow frame, a draw-bar in said guide flexibly connected to the inner ends of said front tillage gangs, relatively longitudinally fixed draft links connected to said front harrow frame and the inner ends of said rear tillage gangs, draft means flexibly connecting said draw-bar to the outer ends of said rear harrow frame whereby the latter will be moved rearwardly with the rearward angling 70 movement of said front tillage gangs, and the pivoted portion of the rear gangs will be moved rearwardly to angle the same and means for actuating adjusting and locking said relatively fixed and movable draft connections and frame units relative to each other as against the forward draft movement of the tractor. 75
- In testimony whereof I have affixed my signature in the presence of two witnesses.
- FREDERICK C. WARNE.
- Witnesses:
- N. P. HENRY,
D. C. UPEESE.
